UNITED STATES PATENT OFFICE.

KENNETH G. CURRIER, OF EAST ORANGE, NEW JERSEY, AND JULES HEINRICH, OF NEW YORK, N. Y., ASSIGNEES TO FRED BUTTERFIELD & CO., INC., OF NEW YORK, N. Y., A CORPORATION OF NEW YORK.

DESIGN FOR A FLOCKED VOILE FABRIC.

Application filed January 23, 1929. Serial No. 29,751. Term of patent 3½ years.

To all whom it may concern:

Be it known that we, KENNETH G. CURRIER and JULES HEINRICH, citizens of the United States, and residents, respectively, of East Orange, in the county of Essex and State of New Jersey, and of the borough of Manhattan, in the city, county, and State of New York, have invented a new, original, and ornamental Design for Flocked Voile Fabric, of which the following is a specification,

reference being had to the accompanying drawing, forming a part thereof.

The figure is a plan view of a portion of a flocked voile fabric, showing our new design.

We claim:

The ornamental design for flocked voile fabric, as shown.

KENNETH G. CURRIER.
JULES HEINRICH.
